Patented Oct. 2, 1917.

2 SHEETS—SHEET 2.

UNITED STATES PATENT OFFICE.

ROBLEY C. MILLARD, OF ATLANTA, GEORGIA.

BLOCK-SIGNALING SYSTEM.

1,241,873.

Specification of Letters Patent.

Patented Oct. 2, 1917.

Application filed November 12, 1914. Serial No. 871,766.

To all whom it may concern:

Be it known that I, ROBLEY C. MILLARD, a citizen of the United States, residing at Atlanta, in the county of Fulton and State 5 of Georgia, have invented certain new and useful Improvements in Block Signaling Systems, of which the following is a specification.

My invention relates to new and useful 10 improvements in block signal systems for railroads, the primary object of my invention being the provision of a simple system by means of which a train passing in either direction along a track will receive warning 15 of trains preceding it in the same direction, following it, or coming toward it along the same track and will also give warning to such trains.

A still further object of my invention consists in so arranging the block signal system 20 that three successive warnings will be given, the first consisting merely in the provision of a visible or audible signal device, the second in a warning application of the air 25 brakes of the train and the third in an emergency application of the brakes.

A still further object of my invention is to so arrange the block signal system that it 30 may be equally as effective for trains running backward as for trains going ahead and so arranged that in either case the trains upon their passage from a block will reset certain of the mechanisms previously 35 set by the train, the arrangement being such that no train can approach within two blocks of another train without receiving suitable warning.

A still further object of my invention is to accomplish the foregoing objects without 40 the employment of a third rail and without maintaining a flow of current through the track rails, the various circuits necessary being momentarily closed between spaced contacts located adjacent the track rails and 45 the track rails and also through the brake actuating circuits of the train, said circuits including brushes or other like contacts for engagement with the contacts disposed near the track.

50 A still further object of my invention is to provide a block signal system which may be quickly and cheaply installed and which will be effective in use and certain in operation.

55 With these and other objects in view, my

invention will be more fully described, illustrated in the accompanying drawings and then specifically pointed out in the claims which are attached to and form a part of this application.

60

In the drawings:

Figure 1 is a diagrammatic view of the mechanism carried by each locomotive operating over roads equipped with my block signal system;

65

Fig. 2 is a diagrammatic view showing three adjacent blocks and the equipment thereof, it being understood that all blocks are duplicates of each other.

Corresponding and like parts are referred 70

to in the following description and indicated in all the views of the drawings by the same reference characters. Furthermore, inasmuch as the various contacts, switches and other parts of each block are identical 75 with corresponding parts of all other blocks, I shall, in the blocks illustrated in the drawings, refer to the parts of but one block by their reference numeral and a distinguishing letter characteristic of such block. 80 This reference is to be considered as a description of the corresponding parts of the remaining blocks illustrated, which parts will be designated by the same numeral but with the distinguishing letter of their particular blocks in junction with the numeral.

85

Referring first to the track mechanisms, attention is particularly directed to Fig. 2 of the drawings in which 10 and 11 indicate the usual rails, it being understood that 90 these rails are each electrically bonded throughout the length of the track in order that they may serve as parts of all metallic circuits. The track, as is usual in signaling systems of this character, is divided into a 95 plurality of blocks, the divisions in this figure being shown by transverse dot and dash lines. Each of these blocks may be of any suitable length and associated with each block are mechanisms controlling the setting 100 of signals of certain blocks ahead and the resetting of signals of certain blocks at the rear. It will of course be understood that these mechanisms, in practice, will be enclosed in suitable housings mounted in any 105 convenient position, usually adjacent the tracks, save for the contact shoes which, of course, must be mounted near the rails and left exposed for engagement by the train carried contacts. Those of the track shoes 110

which coöperate with the mechanism for setting signals ahead of the train are located adjacent the entrance of the respective blocks, while those controlling the resetting of signals at the rear are located adjacent the farther ends of their respective blocks.

I have illustrated, in Fig. 2, three blocks A, B and C, together with the mechanisms associated therewith. Referring to block A, a description of which will suffice for a description of all, it will be seen that a plurality of spaced contact shoes 12^a, 13^a, 14^a, 15^a and 16^a are located at one side of the track and near the entrance of the block, while similar track contacts 17^a, 18^a, 19^a and 20^a are located at the other end of the block, all of these contacts being located adjacent one of the rails of the track, in this instance, adjacent the rail 10. Attention is directed to the fact that the contact 12^a is located the same distance from the rail 10 as the contacts 17^a, 18^a, 19^a and 20^a, while the contact shoes 14^a and 16^a are located somewhat farther from the rail and the contact shoes 13^a and 15^a still farther from the rail, all of the contacts, above mentioned, being consecutively numbered from the entrance of the block. These contact shoes may be of any length found desirable and may be spaced any suitable distance apart although, as a rule, they will be located relatively close to each other. Disposed in a reverse manner, adjacent the track rail 11, are the contact shoes 21^a, 22^a, 23^a, 24^a, 25^a, 26^a, 27^a, 28^a and 29^a. These contacts correspond to the contacts 12^a to 20^a inclusive and are those engaged by a car when passing through the block in the opposite direction. A conductor 30^a joins the contacts 13^a and 14^a, while a conductor 31^a joins the contacts 22^a and 23^a, the remaining contacts being free of all electrical connection with all other contacts. Each block in the system is provided with corresponding contacts or contact shoes located in a similar manner, the corresponding contacts being given the same reference numeral but a characteristic distinguishing letter associated with the numeral.

The block A includes, as part of its mechanism, a switch 32^a including opposed electro-magnets 33^a and 34^a between which is positioned a swingingly mounted armature 35^a which also forms the switch blade, its free end being movable into engagement with the contact 36^a when attracted by the electro-magnet 33^a. The block A is further provided with a second switch mechanism 37^a including opposed electro-magnets 38^a and 39^a and a common swingingly mounted armature 40^a movable into engagement with the contact 41^a when the magnet 39^a is energized. The block A is further provided with a switch mechanism 42^a including opposed magnets 43^a and 44^a having a common armature 45^a forming a switch blade and

movable into engagement with a contact 46^a when the magnet 43^a is energized. A link 47^a connects this switch blade or armature with the free end of a switch blade 48^a which is pivotally mounted intermediate its length and which, when the switch blade 45^a engages the contact 46^a, is adapted to bridge a circuit between the spaced contacts 49^a and 50^a. On the other hand, when the armature 45^a is in its opposite position, this switch blade 48^a is adapted to bridge a circuit through the spaced contacts 51^a and 52^a. Further the block A includes an additional switch mechanism 53^a including opposed electro-magnets 54^a and 55^a and a common armature 56^a adapted, when attracted by the electro-magnet 54^a, to engage a contact 57^a.

Having thus described the track contact shoes and the coöperating switch mechanisms, I will now describe the wiring between them. A conductor wire 58^a leads from the contact shoe 12^a to the electro-magnet 39^a and a wire 59^a leads from this magnet to the track rail 11. A conductor wire 60^a leads from the track contact 14^a, and consequently from the track contact 13^a, the two being electrically connected, to the switch contact 36^a and a wire 61^a leads from the switch blade 35^a to the wire 59^a. A wire 62^a leads from the contact shoe 15^a to the contact 46^a of the switch 42^a and a wire 63^a leads from the switch 45^a to the track rail 10. A wire 64^a leads from the contact shoe 16^a to the contact 57^a of the switch 53^a and a wire 65^a leads from the switch blade 56^a to the wire 63^a and so to the track rail 10.

A wire 66^a leads from the contact 17^a to the electro-magnet 43^a, a wire 67^a leads from this electro-magnet 43^a to the switch contact 52^a, a wire 68^a leads from the co-acting switch contact 51^a to the electro-magnet 54^a and a wire 69^a leads from this electro-magnet 54^a to the wire 65^a and so by way of the wire 63^a to the track rail 10. A wire 70^a leads from the track contact shoe 18^a to the electro-magnet 55^a and a wire 71^a leads from this electro-magnet to the wire 65^a. A wire 72^a leads from the track contact shoe 19^a to the electro-magnet 38^a and a wire 73^a leads from this electro-magnet to the wire 59^a and so to the track rail 11. A wire 74^a leads from the track contact shoe 20^a to the electro-magnet 44^a and a wire 75^a leads from this electro-magnet to the wire 63^a and so to the track rail 10.

Considering now the connections from the track contacts at the other side of the track, a wire 76^b leads from the track contact 21^b to the electro-magnet 33^a and a wire 77^a from this electro-magnet to the wire 59^a and so to the track rail 11. A wire 78^a leads from the track contact 22^a, and consequently the track contact 23^a to the switch contact 41^a, a wire 79^a leading from the switch blade 40^a to the wire 73^a and so to the wire 59^a.

and the track rail 11. A wire 91^a leads from the track contact 24^a to the wire 62^a and consequently to the track contact 15^a. A wire 80^a leads from the track contact 25^a to the wire 64^a. A wire 81^a leads from the track contact 26^a to the wire 66^a and consequently to the track contact 17^a. A wire 82^a leads from the track contact 27^a to the wire 70^a and so to the track contact 18^a. A wire 83^a leads from the track contact 28^a to the electro-magnet 34^a and a wire 84^a leads from this electro-magnet to the wire 73^a and so by way of the wire 59^a to the track rail 11. A wire 85^a leads from the track contact 29^a to that wire leading from the electro-magnet 44^b to the contact 20 of the next block beyond block C.

Line wires 86 and 87, including any suitable source of electrical energy, not shown, preferably extend parallel to the track and at each block, branch wires 88 and 89 lead therefrom. The branch wire 88^a leads to the contact 49^a and includes an electrically operated signal device as at 90^a, while the branch wire 89^a leads to the contact 50^a.

Having thus described the track mechanism proper, together with its wiring, I will now describe the co-acting mechanism carried by the train. It will of course be understood that each train is provided with a separate mechanism, preferably located in the locomotive as the locomotive always forms one element of every train. Referring more specifically to Fig. 1 of the drawings, in which the mechanism is shown diagrammatically, 92, 93 and 94 indicate contact brushes which are supported at the side of the locomotive, in any suitable manner, to permit them to engage the track contacts adjacent the rail 10. These contact brushes are insulated from each other, the brush 92 being adapted to engage the contacts 12, 17, 18, 19 and 20, the contact brush 93 to engage the contacts 14 and 16 and the contact brush 94 to engage the contacts 13 and 15. Corresponding contact brushes 95, 96 and 97 are supported at the opposite side of the locomotive to engage the track contacts adjacent the rail 11 when the locomotive is backing along the track or to engage the contacts adjacent the rail 10 when the locomotive is going ahead along the track in the other direction. It will therefore be seen that one set or the other of these contact brushes will be in position to operate irrespective of the direction in which the locomotive is traveling and whether it is being driven ahead or backward. In Fig. 1 I have illustrated a portion of a locomotive truck, conventionally, at 98 and one of the track contacts 16^a adjacent the track rail 10. I have also shown, at 99, in broken lines, an electrical connection between the track rail 10 and the contact 16^a to represent the closing of a circuit through the wiring of

the block signal system, the various switch mechanisms which may be in this circuit not being shown.

A wire 100 leads from one pole of a storage battery 101, or other suitable source of electrical energy, to the locomotive truck 98, and consequently to the track rail. A three bladed switch, indicated as a whole by the numeral 102 is mounted at any convenient point in the locomotive and includes switch blades 103, 104 and 104' insulated from each other but adapted to be swung simultaneously, being pivoted to contacts 105, 106 and 106' respectively. These switch blades are adapted to engage either the contacts 107, 108 and 108', respectively, or the contacts 109, 110 and 110', according to the position of the switch. A wire 111 leads from the contact brush 92 to the switch contact 107, a second wire 112 also leads from the contact brush 92 to the switch contact 108, and a third wire 112' leads from the contact brush 92 to the switch contact 108'. A wire 113 leads from the contact brush 95 to the switch contact 109, a wire 114 also leads from the contact brush 95 to the switch contact 110, and a wire 115 leads from the contact brush 95 to the switch contact 110'. A wire 116 connects the contact brushes 93 and 96, and a wire 117 connects the contact brushes 94 and 97. Wires 119 and 120 lead from the wires 116 and 117 to electro-magnets 121 and 122, respectively, while wires 123 and 124 lead from these magnets to the switch contacts 105 and 106, respectively, and a wire 118 leads from the other pole of the battery 101 to the switch contact 106'.

Mounted at any convenient point, preferably within the locomotive cab, and communicating with the train pipe of the air brake system, is a valve, conventionally shown at 125 and so constructed that when partially opened, it will vent the train line sufficiently to give a slight and gentle application of the brakes, while, when more widely opened, it will give an emergency application of the brakes. The valve handle 126 is pivotally connected to a link 127 having a threaded end 128. The electro-magnets 121 and 122 are provided with swingingly mounted armatures 129 and 130, respectively, the free ends of which extend past each other and are slotted to receive the threaded end of the link 127. A nut 131 is threaded upon the link 127 to support the armature 130 in such a manner that when attracted by its magnet 122, it will draw the link 127 a sufficient distance to open the valve for a gentle warning application of the brakes, the extent to which the valve will be opened being dependent upon the adjustment of the nut 131. The free end of the armature 129 engages between spaced nuts 132 threaded upon the link 127 in such a manner that upon energization of the magnet 121, the

valve 125 will be fully opened to give an emergency application of the brakes. The electro-magnets are so arranged with respect to each other that after complete movement of the armature 130, because of attraction by its magnet, the armature 129 will still be a considerable distance from its magnet.

As will be more fully pointed out, the engagement of either of the contact brushes 92 and 95 with the track contacts in no way affects any circuits through the electro-magnets 121 and 122, their function being merely to close certain track circuits which either set or reset the various switch mechanisms of the blocks during the passage of the train. On the other hand, assuming that the switch 102 is in the position shown in Fig. 1, an engagement of the contact brush 97 with a track contact in electrical circuit with either of the rails 10 or 11 will cause energization of the electro-magnet 122, current passing from the battery 101, wire 100, locomotive truck 98, rail 10 or 11, as the case may be, and through the track circuit, as will be later explained, to the brush 97, through the wire 117 and wire 120 to the electro-magnet 122, through the wire 124 and switch blade 103 to the wire 114, to the contact brush 95 and from this brush through the wire 115, switch blade 104 and wire 118 to the battery. In like manner, a corresponding circuit through the magnet 122 will be formed if the switch 102 is in reverse position, upon engagement of the contact brush 94 with a track contact in electrical connection with one of the track rails.

Again, if the switch is in the position shown and the contact brush 96 engages a track contact in electrical circuit with one of the track rails, a circuit will be formed through the electro-magnet 121, current passing from the battery through the wire 100, locomotive truck 98, track rail 11 and track circuit to that contact engaging the brush 96 through the wire 116 and wire 119 to the magnet 121, through the wire 123 and switch blade 104 and wire 113 to the brush 95 and from this brush through the wires 115 and 118 to the battery. Furthermore, with the switch reversed, if the brush 93 engages a track contact in electrical connection with either track rail, as shown in Fig. 1, a circuit will be formed through the electro-magnet 121.

At this point it should be noted that all circuits formed through the electro-magnets pass through one or the other of the brush contacts 92 and 95 depending upon which set of contacts is in use and that for this reason either set of contacts may be rendered inoperative by proper positioning of the switch 102. For instance, if the train is proceeding ahead in either direction along

the track, the contact brushes 92, 93 and 94 will be employed, while if the train is backing in either direction, the contact brushes 95, 96 and 97 will be employed.

It will therefore be seen that the track mechanisms previously described need only be so arranged as to electrically connect certain of the track contacts with the track rails, under certain conditions, and to, under other conditions, break such circuits in order to cause either a warning or emergency application of the train brakes under the necessary conditions.

Having thus described both the wiring of the track circuits and co-acting switches and the wiring of the train carried mechanism, I will now explain the operation of the block signal system as a whole. For the purpose of clearness in this explanation, I will first explain the operation of the system by means of which rear end collisions between trains following each other along the track are avoided, assuming first that a train is at a point substantially midway of block A and proceeding in the direction of block B, the contact brushes 92, 93 and 94 of this train being connected in circuit with the battery 101, while the brushes 95, 96 and 97 are out of circuit. Under these conditions, when the contact brush 92 engages the track contact shoe 17^a, current will flow from the battery 101 through the wire 100 to the track rail 10, through the wire 63^a, wire 65^a, wire 69^a, electro-magnet 54^a, wire 68^a, switch blade 48^a, it being assumed that the armatures 56^a and 45^a are in a reverse position to that shown, wire 67^a, electro-magnet 43^a, wire 66^a to the contact shoe 17^a, brush 92, wire 115 and wire 118 to the battery. This circuit will energize the electro-magnets 43^a and 54^a to move their armatures to the positions shown in the drawings and to move the switch blade 48^a to the position there shown. This movement of the switch blade 48^a closes the circuit through the signal light 90^a, the result being that block A has its signal light displayed and also has its signal system set, as will be later fully explained, to give both warning and emergency brake applications to a following train. As the remaining contact shoes between 17^a and the left end of the block deal with the resetting mechanism of the block setting system, they will, for the moment, be neglected and I will assume that the train has proceeded to the position shown conventionally by a portion of a truck at the extreme left end of block A. Suppose now a train enters block A from the block at the right and considering only such contact shoes as have to do with the safe guarding of block A from a train following the first. Under these circumstances, the contact brush 94 of the following train will engage the contact shoe 15^a. A circuit will

then be formed from the battery 101 of the following train, through the wire 100 to the track rail 10, from this rail through the wire 63^a, switch blade 45^a, wire 62^a, contact shoe 15^a, contact brush 94, wire 117, wire 120, electro-magnet 122, wire 124, switch 102, wire 114 contact brush 95, wire 115 and wire 118 to the battery. This circuit will energize the electro-magnet 122 upon the 5 second train to slightly open its air brake valve 125 and give a warning application of the brakes. Of course it will be understood that the engineer may stop his train before receiving this warning application 10 if he notices the signal light 90^a.

If, however, the engineer pays no attention either to the signal light or the warning application of the train and the train still proceeds through block A, its contact brush 20 93 will then engage the contact shoe 16^a. Under these circumstances, a circuit is formed from the battery 101, through the wire 100, to the track rail 10, through the wire 63^a, wire 65^a, switch blade 56^a, wire 64^a, contact shoe 16^a, contact brush 93, wire 116, wire 25 119, electro-magnet 121, wire 123, switch 102, wire 113, contact brush 95, wire 115 and wire 118 to the battery. This circuit will energize the electro-magnet 121 and give an 30 emergency application of the brakes, bringing the train to an absolute stop. It will therefore be clear that it will be impossible for a train to follow another one into a block already occupied by the train being 35 followed.

It will of course be understood that the train ahead has been protected in the same manner all through the preceding blocks. Assuming now that the leading train, that 40 is, the one at the extreme left end of block A proceeds on its way. Upon approaching the left end of block B its contact brush 92 will engage the track contact shoe 17^b to close a circuit through the electro-magnets 43^b and 54^b in the manner previously described in connection with block A and to therefore set block B against a following train. This same brush will then engage the contact shoe 18^b to close a circuit from 45 the battery through the wire 100, track rail 10, wire 63^a, wire 65^a, wire 71^a, electro-magnet 55^a, wire 70^b to the contact shoe 18^b, the contact brush 92, wire 115 and wire 118 to the battery. Under these circumstances, 50 the switch 53^a is opened. This switch 53^a, as we have seen, is the switch through which the circuit for an emergency application of the brakes of a following train is closed. It will therefore be clear that after the first 55 train has reached the track contact 18^b of block B, a train entering block A will receive only a warning application of the brakes.

As the leading train proceeds from block 60 B into block C, its contact brush 92 will en-

gage the contact shoe 17^c to close the switches 42^c and 53^c in the manner explained in connection with the preceding blocks. It will then engage the contact shoe 18^c to open the switch 53^c in the manner explained in connection with block A. After this, it will engage the contact shoe 20^c closing a circuit from the battery 101, through the wire 100, track rail 10, wire 63^a, wire 75^a, electro-magnet 44^a, wire 74^c, contact shoe 20^c, contact brush 92, wire 115 and wire 118 to the battery. This circuit opens the switch 42^a, and consequently the switch 48^a, thereby completely clearing block A.

We have therefore seen that the contact shoes 15, 16, 17, 18 and 20, together with the switches 43, 48 and 53, control the mechanism for the avoidance of rear end collisions, the contacts 15 and 16 being those which close the brake operating circuits upon a following train, the contact 17 that which sets the mechanism in the block which the train is leaving, the contact 18 that which opens the emergency controlling switch in the block at the rear of the train and the contact 20 that which opens the warning application switch in the second block to the rear of the occupied block.

An examination of the contact shoes adjacent the track rail 11 will show that they correspond to similar shoes adjacent the track rail 10 and will operate in like manner for trains following each other along the track from block C toward block A. A detailed description of their operation is believed to be unnecessary as being substantially identical with that above described.

Before giving a description of the block signal system in connection with approaching trains, I wish to point out that the position of the switches 32 and 37, which are switches controlling the signal system for this purpose, are normally in the position shown in blocks A and C. The switches 37 105 are released by the magnets 38 and closed by the magnets 39, the closing of circuits through these magnets being governed by the track contacts 12 and 19 adjacent the track rail 10, and consequently by trains 110 passing from the right to the left, that is, from block A toward block C, while the switches 32 are released by the magnets 34 and closed by the magnets 33, the circuits 115 through which are controlled by engagement with the track contacts 21 and 28 adjacent the track rail 11, and consequently by trains 120 passing along the track in the opposite direction, that is, from the direction of block C toward block A.

Assuming that a train enters block A, moving toward block C, its contact brush 92 will engage the track contact shoe 12^a. Under these conditions, a circuit will be closed from the battery 101 of such train, 130

through the wire 100, track rail 11, wire 59^b to the electro-magnet 39^b, through the wire 58^a to the contact shoe 12^a, contact brush 92, wire 115 and wire 118 to the battery. This will close the switch 37^b and set block B against a train approaching from block C. Assuming a train approaches from block C, its contact brush 92 will engage the contact shoe 21^b closing a circuit 10 from the battery 101 of its locomotive equipment through the wire 100, track rail 11, wire 59^a, wire 77^a, electro-magnet 38^a, wire 76^b, contact shoe 21^b, contact brush 92, wire 115 and wire 118 to the battery. This will 15 close the switch 32^a and, as will be later explained, close block A against a train approaching from the right.

As soon as the second train, approaching block A from the direction of block C, has 20 advanced sufficiently to bring its contact shoe 94 into engagement with the contact brush 22^b, a circuit will be closed from the battery 101 of such train, through the wire 100, track rail 11, wire 59^b, wire 79^b, switch blade 40^b, wire 78^b, contact shoe 22^b, contact brush 94, wire 117, wire 120, electro-magnet 122, wire 124, switch 102, wire 114, wire 115 and wire 118 to the battery. This will 25 energize the magnet 122 upon the train approaching from block C and give a warning application of the brakes upon such train.

Should the train thus warned continue toward block A, its contact brush 93 will 30 immediately engage the track contact shoe 23^b when a circuit will be formed from its battery 101, through the wire 100, track rail 11, wire 59^b, wire 79^b, switch blade 40^b, wire 78^b, contact shoe 23^b, contact brush 93, wire 116, 35 wire 119, electro-magnet 121, wire 123, switch 102, wire 113, contact brush 95, wire 115 and wire 118 to the battery. This circuit energizes the electro-magnet 121 and gives an emergency application of the brakes 40 and therefore absolutely stops the train.

If the train approaching from block C had 45 set block A against a train approaching in the opposite direction before such train entered block A, similar circuits would be 50 closed through the brake actuating mechanism of such train when its contact brushes 94 and 93 engage the track contact shoes 13^a and 14^a. As these circuits are formed in the same manner as those above described, this 55 explanation need not be repeated.

I will assume, however, that the train approaching from the right had already passed the track contacts 13^a and 14^a. Of course if this were the case, the train approaching 60 block A from block C would be stopped opposite the track contact shoe 23^b. However, a train approaching block B in block A would continue until it entered block B and engaged the contact shoes 13^b and 14^b when 65 first a warning and then an emergency appli-

cation of the brakes would be received by closing of circuits through the switch 32^b, which switch had been set against a train approaching from the direction of block A by the train approaching from the direction of block C when entering block C. Therefore, it will be seen that the train approaching from block C will be stopped opposite the contact shoe 23^b, while the train approaching from block A will be stopped opposite the contact 14^b. In other words, the trains will be brought to an absolute stop at a distance of nearly a block from each other.

In order to explain the resetting of the signaling system, I will assume that a train 80 has entered block A from the right, that is, moving toward block C and has set block B, as previously explained, against a train approaching from block C toward block A. I will further assume that conditions are normal, that is, there is no train approaching block A from the direction of block C. Under these conditions, the train will pass through block A into block B, engaging the contact shoe 12^b to set block C against a train approaching from the left and will then continue through block B until its contact brush 92 engages the track contact shoe 19^b. Under this condition, a circuit will be formed from the battery 101, through the 85 wire 100, track rail 11, wire 59^b, wire 73^b, electro-magnet 38^b, wire 72^b, track contact shoe 19^b, contact brush 92, wire 115 and wire 118 to the battery. This circuit will energize the electro-magnet 38^b and open the 90 switch 37^b, thereby clearing block B against a train approaching from the direction of block C and leaving the block in its original condition.

From the foregoing description, it will be 95 apparent that the block setting and resetting or releasing mechanism for setting and resetting the blocks against following trains and for setting and resetting the blocks against approaching trains in no way interfere with each other and that all trains will 100 operate the block signal system to automatically keep trains from approaching within one block of them in either direction.

It will of course be understood that I do 105 not wish to limit myself to the specific brake valve controlling and actuating mechanism, as illustrated in Fig. 1, as various other devices or systems may be found applicable in connection with the track wiring system 110 shown in Fig. 2. For instance, the form of brake actuating mechanism disclosed in my copending application for a safety appliance for railway trains, filed July 6, 1913 and bearing the Serial No. 746,650 may be employed in place of the above described mechanism, if preferred.

Having thus described the invention, what is claimed as new is:

1. A block signal system including a track,

- a plurality of circuit breakers, a plurality of contacts adjacent the track, circuits normally open between certain contacts and the track for closing the circuit breakers when 5 the circuits are closed, circuits normally open between certain other contacts and the track for opening the circuit breakers when such circuits are closed, circuits through the circuit breakers when the latter are closed 10 which are open between certain other contacts and the track, air valve controlling mechanism carried by the locomotive, circuits upon the locomotive including contact shoes adapted for engagement with the latter contacts to operate the air valve controlling mechanism when said latter track circuits are closed, additional circuits upon the locomotive including contact shoes adapted for engagement with the first mentioned contacts for completing circuits between said contacts and the track to close the circuit breakers, and still further circuits upon the locomotive including contact shoes for engagement with the second mentioned contacts for closing circuits between them and the track for opening the circuit breakers.
2. A block signal system including electrically bonded track rails, a locomotive 30 carried air brake valve, magnets for giving warning and emergency openings to the valve, locomotive carried signal circuits, certain of which pass through the magnets, each signal circuit including a contact brush, 35 contact shoes disposed adjacent the track and engageable by the brushes, and means including relays operable by engagement of certain shoes by the brushes in said signal circuits not through the magnets for placing 40 certain other shoes in electrical connection with a track rail, whereby engagement with one of said latter shoes by one of the brushes in circuit with one of the magnets will close its circuit.
- 45 3. A block signal system including electrically bonded track rails, a locomotive carried air brake valve, magnets for giving warning and emergency openings to the valve, locomotive carried signal circuits, 50 certain of which pass through the magnets, each signal circuit including a contact brush, contact shoes disposed adjacent the track and engageable by the brushes, means including relays operable by engagement of 55 certain shoes by the brushes in said signal circuits not through the magnets for placing certain other shoes in electrical connection with a track rail, whereby engagement with one of said latter shoes by one of the 60 brushes in circuit with one of the magnets will close its circuit, and means operable by engagement of certain shoes by certain
- brushes not in the magnet circuits for rendering the shoes which have been placed in electrical connection with a track rail inactive. 65
4. A block signal system including electrically bonded track rails, a locomotive carried air brake valve, magnets for giving warning and emergency openings to the valve, locomotive carried signal circuits, certain of which pass through the magnets and each of which includes a contact brush, contact shoes disposed adjacent the track and engageable by the brushes, means including relays operable by engagement of certain shoes by the brushes in said signal circuit not through the magnets for placing certain other shoes in electrical connection with a track rail, whereby engagement with one of said latter shoes by one of the brushes in circuit with one of the magnets will close its circuit, a track signal circuit, and means operable by one of the relays controlling the signal circuit. 70 75 80 85
5. In block signal systems, a track, a plurality of track contacts, a train carried signal circuit, a train carried circuit for controlling track circuit conditions, each of such circuits having brushes for engagement with the track contacts, a pair of relays adapted to be energized by engagement of certain of the brushes with one of the track contacts and when energized to electrically connect a pair of track contacts with the track, and a pair of spaced track contacts in circuit each with one of the relays whereby the relays will be successively returned to normal by engagement of the pair of track contacts by one of the brushes. 90 95 100
6. In block signal systems, a track, a plurality of track contacts, a train carried signal circuit, a train carried circuit for controlling track circuit conditions, each of such circuits having brushes for engagement with the track contacts, a pair of relays adapted to be energized by engagement of certain of the brushes with one of the track contacts and when energized to electrically connect a pair of track contacts with the track, a pair of spaced track contacts in circuit each with one of the relays, whereby the relays will be successively returned to normal by engagement of the pair of track contacts by one of the brushes, a track signal circuit, and a switch controlling the track signal circuit and operated by one of the relays. 105 110 115

In testimony whereof I affix my signature in presences of two witnesses.
